VARIABLE DISPLACEMENT PUMP UNIT

Albert P. Smith, Mountain Grove, Mo.

Application June 6, 1952, Serial No. 292,139

4 Claims. (Cl. 103—162)

This invention relates generally to hydraulic transmissions and is directed particularly to a transmission of such type which is piston operated.

A principal object of the present invention is to provide an improved variable displacement pump unit for use in a hydraulic transmission mechanism, as hereinafter more specifically pointed out, wherein by means of opposing driving and driven piston units rotary power is transmitted in varying degrees of speed from a drive shaft to a driven shaft.

Another object of the invention is to provide, in a manner as hereinafter set forth, a variable displacement pump unit for use in a hydraulic transmission mechanism employing opposing reciprocating pistons with control means for varying the extent of travel of the pistons whereby rotary power may be transmitted from the drive shaft to the driven shaft in smoothly changing increments from neutral or stationary position to maximum speed position.

A still further object of the invention is to provide a variable displacement pump unit of the character above set forth wherein such oppositely working pistons have their extent of travel varied by a swash plate interposed between the pistons and a control element.

Still another object of the invention is to provide, in a manner as hereinafter set forth, a variable displacement pump unit employing reciprocating pistons connected with a manually oscillatable and adjustable swash plate, with a centrifugally operated governor means which as the rotary speed of the drive shaft increases permits gradual increasing of power and speed in the driven pistons and the driven shaft with which they are connected.

A still further object of the invention is to provide, in a manner as hereinafter set forth, a fluid bypass means between the driving pistons and the driven pistons whereby the transmitted power can be reduced as desired without reducing the speed of rotation of the drive shaft.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view partly in elevation and partly in longitudinal section of a fluid transmission constructed in accordance with the present invention.

Figure 2 is a central longitudinal section taken substantially on the line 2—2 of Figure 1.

Figure 3 is a transverse section taken substantially on the line 3—3 of Figure 2.

Figure 4 is a transverse section taken substantially on the line 4—4 of Figure 2.

Figure 5 is a view in elevation of the control ring, a portion being broken away.

2

Figure 6 is a diagrammatic view illustrating the form of the adjacent interengaging teeth between a swash plate and an encircling ring gear and illustrating the manner in which the swash plate teeth engage the ring gear teeth.

5 Figure 7 is a face view of one of the control valve housings.

Referring now more particularly to the drawings the numeral 10 generally designates a drive shaft to which power is applied by any suitable means, not shown, while the driven shaft, which is operatively coupled with the transmission mechanism about to be described, is generally designated 12.

In accordance with the present invention the rear end of the drive shaft 10 is enclosed in and extends axially through the cylindrical driving unit shell 16 which is closed at its outer end by the head 18, secured by suitable cap screws 20 to the out turned flange portion 16a of the shell 16.

The center of the head 18 has an opening 22 through which the shaft passes and upon the inner side of the head is a bearing race 24 in which is positioned the anti-friction or bearing unit which is generally designated 26 and through which the shaft passes and in which it is supported.

25 The inner end of the shell 16 has the inturned flange 16b which is positioned against one face of the circular division wall which is generally designated 28 and to which it is secured by cap screws 30 which pass through the flange 16b into the wall 28.

30 The wall 28 has in its two opposite faces the oppositely directed bearing recesses 32 in which are mounted the anti-friction units 34 and as shown, the unit 34 which is directed into the shell 16 has the rear end of the drive shaft 10 stepped therein.

35 Upon the opposite side of the division wall 28 is a cylindrical shell 36 of the same character as the shell 16 and constituting the driven unit shell or housing. This shell 36 has at its forward end the inturned flange 38 which bears against the adjacent face of the division wall 28 and is secured thereto by cap screws 40 while at the outer end the shell 36 has the out turned flange 41.

40 The numeral 42 designates the driven unit shell head which is secured to the flange 41 by screws 43. In the center of the head 42 is a shaft opening 44 leading into the inwardly directed flange 45 which is concentric with the opening 44 and which provides a cup for the bearing unit 46.

45 The driven shaft 12 extends through the opening 44 and is supported by the bearing unit 46 and has its inner or forward end stepped as shown in the adjacent anti-friction or bearing unit 34 carried by the wall 28.

50 From the foregoing it will be seen that the shafts 10 and 12 are maintained in end aligned relation and are supported for independent rotation within their respective shells or housings.

55 The division wall 28 between the shells 15 and 36 is provided with the two concentrically arranged circular or arcuate fluid transfer chambers 47 and each of these chambers is outlined by a continuous channel 48 in which is positioned a sealing ring 49 of a suitable metal such as cast iron, bronze or the like, which extends outwardly beyond the adjacent face of the wall 28, for the purpose hereinafter set forth.

60 65 Within the driving unit shell 16 is a circular cylinder block which is generally designated 50. This block has formed therein around the axial center thereof the circularly arranged series of axially directed piston cylinders 51 which open through the inner end of the block as shown while the outer ends of such cylinders open into the circular chamber 52 which is formed in the outer

end of the block and which is defined by the circular wall 53.

The chamber 52 opens into or has formed in the central part thereof within the circular area defined by the series of cylinders 51, the central circular pocket 54 which is provided for the purpose hereinafter set forth.

The central part of the circular cylinder block provides a hub 55 through the center of which is formed the shaft opening 56. The inner portion of the shaft 10 extends through this opening 56 and is secured to the hub by the key 57 or in any other suitable manner. Thus it will be seen that the cylinder block 50 is secured to the shaft 10 to turn therewith and the inner end of the block bears against the adjacent packing 49 which encircles the fluid transfer chambers and it will also be seen that the centers of the cylinders are arranged in an arc or circular path which lies in the center of the arcuate fluid transfer chambers. Also the diameters of the cylinders is not greater than the width of the fluid chambers so that the packing strips at the inner and outer sides of the chambers will lie outside of the cylinders to prevent leakage of fluid from the cylinders between the cylinder block and the adjacent face of the division wall 28.

Lying within the pocket 54 is a plate 58 which carries on the face directed away from the hub 55, a pair of pivot ears 59. This plate is of annular form and encircles the shaft 10 as shown and in opposed relation with the plate 58 and spaced therefrom is a coacting outer plate 60 which encircles the shaft 10 and which carries an outwardly extending sleeve 61 which surrounds the shaft.

The inner face of the plate 60 carries a pair of ears 62 which are in opposed relation with the ears 59 for cooperation therewith in the manner about to be described.

Each pair of opposing ears 59—62 carries a centrifugal weight unit which comprises an arcuate arm 63 having an end pivoted to the adjacent ear 59 and a link 64 having an end pivoted to the adjacent ear 62 and having its other end pivotally connected to the arm 63 as indicated at 65. As shown each arm 63 extends outwardly beyond the adjacent link 64 and carries on its outer end a weight member 66.

Encircling the shaft 10 and interposed between the plates 58 and 60 is a coiled expansion spring 67 which constantly urges the outer plate 60 away from the inner plate 58 and consequently tends to draw the centrifugal weights 66 inwardly.

Encircling the shaft 10 between the head 18 and the outer end of the cylinder block 50 is a control ring 68 in which is fixed the annular bearing unit 68'.

The control ring 68 has formed integral therewith the radially extending arm 69, for the purpose hereinafter described.

The numeral 70 generally designates a swash plate which is centrally apertured and carries the outwardly projecting hub 71 which has the conical passage therethrough through which extends the sleeve 61. As shown the narrow end of the hub passage 72 is toward the inside of the machine or adjacent to the plate 16.

The hub 71 is fitted to the inside of the bearing unit 68' whereby the swash plate can rotate with the cylinder block while the control annulus or ring 68 remains stationary.

The control ring has at diametrically opposite sides and in a line perpendicular to the radial line of the arm 69, radial arms 73 which terminate in the right angularly disposed pivot ears 73a which position adjacent to the inner sides of the shell 16, as shown in Figure 1.

Threaded into the openings 74 in the said opposite sides of the shell 16, are the trunnions 75, each of which extends through an apertured ear 73a. Thus the control ring 68 is supported for turning movement on the aligned supporting trunnions 75 and as will be readily seen, when the control ring is turned on its supporting trunnions

it will also turn with it the swash plate 70 which is in a plane parallel with the control ring.

Manual control of the ring 68 is provided by the rod 173 which extends longitudinally through the shell 36, the division wall 28 and into the shell 16 and is in end alignment with the outer end of the control ring arm 69 as shown.

Within the shell 16 and encircling the free inner end of the rod 173 is a pull spring 174, one end of which is secured to the rod 173 as at 175, while the other end is secured to the outer end of the arm 69 as indicated at 176.

The periphery of the swash plate 70 has formed therearound the spaced teeth 77 which are tapered from the transverse center toward the front and rear edges as illustrated in Figure 6. The function of these teeth is hereinafter described.

Inwardly of the annular series of teeth 77 the swash plate 70 has formed therein the circular series of sockets 78 equaling in number the adjacent piston cylinders 51 and in each of these sockets is positioned the spherical or ball end 79 of a connecting rod 80.

The other or inner end of the connecting rod 80 has a similar spherical head 81 which is secured in a piston 32 slidably positioned in an adjacent cylinder 51.

Positioned against the inner face of the swash plate 70 and secured thereto in any suitable manner is a retaining plate 70' which engages the heads 79 of the connecting rods to maintain the heads in their sockets 78.

The numeral 83 designates a ring gear which is secured to the outer end of the annular wall 53 as shown and which has the internal teeth 84. This ring gear 83 is of an inside diameter to receive the annular series of swash plate teeth 77 which fit between the teeth 84 of the ring gear. As will be readily apparent since the swash plate 70 turns on an axis which passes diametrically through the ring gear, certain of the swash plate teeth will be at all times connected between the ring gear teeth and as the plate swings on its axis into a common plane with the ring gear 83 more of the teeth of the plate and gear will come into mesh until, when the plate and gear are in a common plane all of the teeth upon the two members will be engaged.

Within the driven unit shell 36 there is positioned concentrically with the driven shaft 12, a circular cylinder block 85 corresponding to the cylinder block 50, in which are formed the series of piston cylinders 86 corresponding in number to the cylinders 51.

The outer end portion of the block 85 is chambered as indicated at 87, whereby is formed the circular wall 88 and the cylinders 86 open into the chamber portion 87 and at their inner ends open through the inner end of the block, which end is positioned against the annular packing rings 49 in the same manner as the block 50.

The central portion of the block 85 provides a hub 89 having the bearing opening 90 therethrough through which extends the shaft 12.

As illustrated the end of the shaft 12 which is adjacent to the bearing unit 34, is keyed, as at 91, to the hub 89 so that rotary movement imparted to the block 85 will be transmitted to the shaft 12.

Encircling the rear end portion of the shaft 12, within the shell 36 and adjacent to the head plate 42 is a ring 92 corresponding to the ring 68, which carries the diametrical arms 93 which terminate in the mounting ears 93a. These ears 93a are mounted upon pins 94 fixed in the wall of the shell 36. The ring 92 is maintained in a plane oblique to the shaft 12, as shown, by suitably positioned stops 92a carried upon the inner face of the head 42, as shown in Figure 2.

The forward or inner face of the ring 92 is recessed as at 95 to receive the annular bearing unit 96, in which unit is secured the hub portion 97 of a swash plate 98.

This hub and plate has the conical opening 99 there-

through which permits the plate to rotate in a plane oblique to the shaft 12.

The periphery of the swash plate 98 has formed there-around the gear teeth 100 which are of the same form as the teeth 77 and encircling the swash plate and secured to the edge of the wall 88 is the ring gear 101 having the internal teeth 102.

The plate 98 is of substantially the same design as the plate 70 and is provided, like the plate 70, with a plurality of sockets 103 arranged in an annular row on the side of the plate facing the cylinders 86 and in each socket is mounted the spherical head 104 of a connecting rod 105. The other end of each rod extends into a cylinder 86 and is connected by the head 106 with the piston 107 located in the cylinder.

Secured on diametrically opposite sides of the machine and extending across the division wall 28 in which the two arcuate fluid transfer chambers are formed, are fluid transfer valve housings 108. Each of these housings has a central chamber 109 which communicates with a port 110 extending radially in the division wall 28 from the adjacent fluid transfer chamber 47.

At each end of the valve housing 108 is a chamber 111 which communicates with a port 112 formed through the adjacent housing wall to communicate with the interior of the housing in which is encased the cylinder block pistons and other units. In other words one end chamber 111 communicates with the interior of the cylindrical shell while the other end chamber 111 of each valve housing 108 communicates with the interior of the shell 16.

The central chamber 109 of each valve housing 108 is in communication with the two adjacent end chambers 111 through the valve port 113 and these valve ports are provided on corresponding sides with the annular valve seats 114.

One of the end chambers 111 of each valve unit has a tapped opening therein as indicated at 115, in which is threaded the guide collar 116 and through this guide collar extends a valve stem 117 which passes through the adjacent end chamber 111 and through the central chamber 109 and carries the two valve disks 118, each of which is formed to engage a seat 114.

The guides 116 are arranged in corresponding ends of the valve housings 109 and the stems 117 extend through apertures in radially extending guide ears 119 carried by the head plate 42.

Suitable means is provided, not shown, for effecting the movement of the rods 117 for unseating or seating the valve disks 118 and also suitable means, not shown, is provided for effecting the actuation of the rod 73.

In the operation of the transmission mechanism the shells 16 and 36 are filled with a suitable fluid which also fills the transfer chambers 47. When rotary motion is applied to the drive shaft 10 such rotary movement will be transmitted to the cylinder block 50. During the stationary period of the transmission mechanism the spring 67 will force the swash plate 70 and control ring 67 to turn to a position in a plane perpendicular to the drive shaft thus pulling the centrifugal weights 66 inwardly. During such self adjustment of these parts under the action of the spring 67 the pull spring 74 will be stretched and put under some tension.

As the speed of rotation of the shaft 10 and block 50 increases the centrifugal force will move the weights 66 outwardly, such weights being connected through the medium of the arms 66 with the plate 58 which is secured to the block and this will retract the plate 60 which is pressing against the swash plate 70 thus permitting the pull spring 74 to turn the control ring 68 on the supporting trunnions 75.

The spring 74 will continue to move the control ring and swash plate 70 to the extent permitted by the centrifugal weights or by the rearward movement of the plate 60 under the pull of the weights whereupon the swash plate will remain at the selected angle to the drive

shaft and as the rotary motion is transmitted through the cylinder block to the swash plate through the medium of the connecting gear teeth 77 and 84 the driving pistons 82 will be moved in and out in their cylinders as will be readily apparent.

As each piston 82 moves outwardly or away from the adjacent fluid transfer chamber fluid will be drawn into the cylinder from the opposing cylinder 86 and reverse movement of the piston 82 will force the fluid back into the opposite cylinder so as to force the opposite cylinder 107 therein outwardly thereby transmitting pressure to the plate 98 to cause such plate to rotate and thereby transmit corresponding rotation to the cylinder block 85 through the interconnecting teeth 100 and 102.

It will be understood, of course, that during the operation above described the valves 118 will be closed so that fluid in the transfer chambers 47 will be retained therein and in the piston cylinders opening into such chambers.

If it should be desired to slow up the rotation of the driven shaft the valve stems 117 will be shifted to open the valve members 118 or disengage them from their seats 114 so that the fluid in the transfer chambers will be permitted to flow into and out of the shells 16 and 36 as the pistons reciprocate and the driving force against the pistons 107 will be reduced or stopped entirely. Thus it will be seen that the power transmitted to the driven shaft 12 from the drive shaft can be regulated without having to reduce the speed of operation of the engine operating the drive shaft.

It will also be apparent that by adjusting the rod 173 the pull of the spring 174 upon the control disk 68 can be increased or lightened as desired to thus effect the desired angular adjustment of the swash plate 70.

If it is desired to reverse the direction of rotation of the driven shaft 12 such reversal is accomplished by shifting the rod 173 inwardly to bring the inner end against the extension 69 of the control ring 68 to thereby oscillate the ring 68 from the position in which it is shown in Figure 2 to a reversely disposed angular position or, in other words, to a position in which it is oblique to the shaft 10 with the extension arm 69 inclined toward the front. This reversal of the oblique disposition of the control ring will shift the lowermost piston 82 rearwardly and shift the uppermost piston 82 forwardly in their cylinders with the other pistons in corresponding intermediate positions. Accordingly upon rotation of the cylinder block 55 the piston 82 which is at the uppermost position in Figure 2 will start to move rearwardly and the piston 82 which is lowermost in this figure will start to move forwardly to thereby apply pressure, together with the other pistons, in the reverse direction to that in which it was previously applied with a consequent reversal of the direction of rotation of the plate 98 and the cylinder block 89 connected thereto through the medium of the pistons and piston rods 105 and 107.

I claim:

1. In an apparatus of the character set forth, a rotary cylinder block, means supporting the block for rotation, said block having cylinders extending lengthwise of its axis of rotation, piston members positioned for reciprocatory movement in said cylinders, a circular plate centrally traversed by said axis, means supporting the plate for both rotational movement around said axis and for rocking movement on an axis perpendicular to said rotational axis, piston rods operatively coupling the plate and said pistons, means for effecting rocking adjustment of the plate between a position in which it is in a plane perpendicular to the first axis and a position in which it is in a plane oblique to the first axis, a gear coupling between the periphery of the plate and the cylinder block by which driving connection is maintained between the plate and cylinder block in all positions of adjustment of the plate, said block having an end provided with an open chamber, said plate being positioned to have a portion enter the chamber when rocked to an oblique po-

sition, and said gear coupling comprising an internal tooth ring gear carried by the block and encircling the plate and gear teeth carried by and around the edge of the plate.

2. The invention according to claim 1, with spring means interposed between the block and the plate and urging rocking movement of the plate to a position in which it lies in a plane perpendicular to the first axis, and centrifugally actuated means connected to and rotatable with the block for retracting the spring means.

3. In an apparatus of the character set forth, a rotary cylinder block, means supporting the block for rotation, said block having cylinders extending lengthwise of its axis of rotation, piston members positioned for reciprocatory movement in said cylinders, a circular plate positioned to have said axis pass centrally therethrough, an annular member encircling said axis and having a radially extending arm, a pair of bearing arms carried by said member at diametrically opposite positions thereon, pivot members engaged by the bearing arms and supporting the annular member for rocking movement on an axis intersecting and perpendicular to the first axis, an annular hub carried by the plate, a bearing coupling between said hub and said annular member by which the plate may rotate with the block, a plurality of piston rods each pivotally coupled at one end to the plate and having operative connection at its other end with a piston, means connected with the first radial arm of the annular member for rocking the member and plate on the second mentioned axis, a coupling between the periphery of the plate and the cylinder block by which driving connection is maintained in all positions of angular adjustment of the annular member and plate with respect to the first axis,

said block supporting means comprising a shaft, a thrust member slidably positioned on the shaft between a part of the block and the plate and bearing against the plate, spring means constantly urging the thrust member toward

5 the plate, and centrifugal members connected between the thrust member and the block and acting under centrifugal force to retract the thrust member.

4. The invention according to claim 3, wherein said cylinder block has an end provided with a chamber opening toward the plate and annular member, said plate being positioned to have a portion received within the chamber when the plate is rocked to an oblique position, and said coupling between the periphery of the plate and the cylinder block comprising an internal tooth ring gear secured to the said end of the cylinder block and lying in the plane of the axis of rocking movement for the annular member, and gear teeth carried by and around the edge of said plate, a number of which gear teeth are in constant mesh with teeth of the ring gear.
